PAPERBOARD CARRIER

William R. Davis, Atlanta, Ga., assignor, by mesne assignments, to Atlanta Paper Company, a corporation of Ohio

Application March 17, 1955, Serial No. 494,855

4 Claims. (Cl. 220—105)

This invention relates to paperboard carriers of the type arranged to contain and display a group of articles and to provide for convenient carrying of the article group; and more particularly to an improved arrangement for a carrier of this sort by which the carrier structure is greatly strengthened during carrying as well as being made readily adjustable for stacking.

The improved paperboard carrier structure of the present invention is adapted especially for use in the merchandising of beverage glasses, and is described in detail further below in relation to an embodiment arranged specifically for this purpose, and from which it will be seen that the carrier structure described may be advantageously used as well for similar handling of other articles in general, such as jars, cans, bottles and the like, either filled or unfilled.

Generally described, the present invention provides a carrier structure that is characterized by a medial strut member connected between the bottom wall of the carrier and the handle portion thereof so that the bottom wall is supported from the handle portion when the latter is raised above the tops of articles in the carrier for carrying, and further arranged for collapsing laterally to allow depression of the handle portion from its raised carrying position to a disposition below the article tops so that the carrier, while filled with articles, may be stacked with other filled carriers.

The present invention is described further below in connection with the accompanying drawings in which:

Fig. 1 is a perspective view of a paperboard carrier embodying the present invention, with articles arranged therein indicated in dotted lines, and with the handle portion illustrated in the position it would assume for carrying;

Fig. 2 is an end view of the carrier illustrated in Fig. 1 with the handle portion shown in the depressed position, and with the raised position indicated in dotted lines;

Fig. 3 is a plan view corresponding to Fig. 2 with the intermediate partition strips broken away to show the laterally collapsed arrangement of the medial strut member;

Fig. 4 is a side view corresponding to Fig. 2 with the side wall broken away to show the strut member collapsed laterally between the articles positioned in the carrier;

Fig. 5 is a plan view of a blank suitable for forming the carrier illustrated in Fig. 1;

Fig. 6 is a similar plan view illustrating the first step in gluing and folding the blank of Fig. 5 to form the carrier of the present invention; and

Fig. 7 is a further plan view showing the blank of Fig. 5 completely folded and glued to complete the carrier in collapsed form ready for erection to the form illustrated in Fig. 1.

Referring now in detail to the drawings, and more particularly at first to Fig. 1, the carrier shown is designated generally by reference numeral 10 and comprises a

2

handle portion 12, composed of panels 14 and 16 foldably hinged along the top edges thereof and having coinciding hand openings 18 and 20 formed therein. Handle panels 14 and 16 are secured together, as by glue or the like, in face-to-face relation, as best shown in Fig. 2, to form the handle portion 12.

Carrier 10 further comprises top wall panels 22 and 24, each of which has spaced openings 22' and 24' therein forming end and intermediate partition strips 26 and 28 foldably extending from the lower edges of the respective handle panels 14 and 16 for positioning articles, such as beverage glasses G as indicated by dotted lines in Fig. 1, at each side of the handle portion 12. The extending ends of these partition strips 26 and 28 are in turn foldably connected at the top edges of opposed side wall panels 30, the lower edges of which are foldably connected by a medially foldable bottom wall 32 formed by bottom wall half laps 34 and 36. The bottom wall half laps 34 and 36 are proportioned in a width sufficiently less than the width of top wall panels 22 and 24 to incline the side wall panels 30 in relation to the form of the beverage glasses G, and to engage the bottoms of the beverage glasses G at positioning slots 30' formed adjacent the lower side wall edges.

One of the bottom wall half laps 34 has a securing flap 38 foldably joined thereto by which it is arranged for securing to the other bottom wall half lap 36. This other half lap 36 is foldably connected with the previously mentioned medial strut member, which is designated by the reference numeral 40, and the securing flap 38 of the half lap 36 may be fixed in face-to-face relation at the lower portion of this strut member 40. The strut member 40 is arranged as a medial partition extension on the bottom wall half lap 36 and extends therefrom to reach upwardly between the panels 14 and 16 of the handle portion 12 and have an upper edge portion thereof secured between these panels 14 and 16, so as to support the bottom wall 32 from the handle portion 12 when it is raised above the tops of the articles G in the carrier 10 for carrying as illustrated in Fig. 1.

The medial strut member 40 is further arranged to allow depression of the handle portion 12 below the tops of the articles G, as illustrated in Fig. 2, so as to provide for stacking of a group of loaded carriers 10 when desired. For this purpose, the strut member 40 is intermediately notched as at 42 and 44 in alignment with the openings 22' and 24' that form the partition strips 26 and 28 in the top wall panels 22 and 24, and is transversely scored at 46 for folding centrally of these notches 42 and 44, as well as being scored at 48 and 50 to fold above the bottom wall securing flap 38 and at the bottom edge of the handle portion 12. The result of this arrangement is to form strap portions 52 in the medial strut member 40 that are laterally collapsible and that are shaped for collapsing or folding laterally beneath the intermediate partition strips 28 and between adjacent articles G in the carrier 10, as illustrated in Figs. 2, 3 and 4, to allow depression of the handle portion 12 readily whenever desired, while still maintaining the strut member 40 fixed between the bottom wall 32 and handle portion 12 for supporting the bottom 32 therefrom when raised for carrying.

Fig. 5 shows a form of blank suitable for forming the carrier 10 as described above, and together with Figs. 6 and 7 illustrates the manner in which this blank is folded and secured in forming the carrier 10. As shown in Fig. 5, the panels 14 and 16 of the handle portion 12 are arranged intermediately in the blank, with the top wall panels 22 and 24, having the openings 22' and 24' therein to form the partition strips 26 and 28, disposed at the opposite edges of the handle panels 14 and 16. The opposed side wall panels 30 are connected at the re-

spective extending edges of the partition strips 26 and 28, and have the respective bottom wall half laps 34 and 36 connected at their opposite edges, with the securing flap 38 arranged on the half lap 34 and the medial strut member 40 on the half lap 36.

The procedure of folding and securing the above noted blank to form the carrier 10 consists in first applying glue or the like at a restricted area of the inner face of handle panel 16, as indicated by stippling in Fig. 5, and then folding the bottom wall half lap 36 and medial strut member 40 inwardly over the adjacent side and top wall panels 30 and 24 so as to secure the extending edge portion of the strut member 40 at the inner face of handle panel 16, as illustrated in Fig. 6; and then folding the other bottom wall half lap 34 inwardly over the adjacent side wall panel 30 and applying glue or the like to the exposed faces of the securing flap 38 and the handle panel 14, as indicated in Fig. 6, so that the upper portion of the blank in Fig. 6 can be folded downwardly about the top edge connection between the handle panels 14 and 16 to complete the carrier in collapsed form, as illustrated in Fig. 7, ready for erection and loading with the articles G.

The present invention has been described in detail above for purposes of illustration only and is not intended to be limited by this description or otherwise except as defined in the appended claims.

I claim:

1. A paperboard carrier comprising a medial handle portion, foldable partition strips extending transversely on each side of said handle portion at the bottom edge thereof, opposed side walls foldably secured at the extending ends of the partition strips at each side of said handle portion, bottom wall half laps foldably secured at the bottom edges of each of said side walls and foldably joined medially of said carrier, and a medial strut member foldably secured to said bottom wall half laps and to said handle portion for tying said half laps to said handle portion when raised for carrying, said strut member being recessed to form intermediate strap portions aligned with certain of said partition strips and being substantially the same width thereof, and said strap portions being intermediately foldable for collapsing laterally beneath said partition strips to allow depression of said handle portion from said raised carrying position.

2. In a paperboard carrier having a medial handle portion, end and intermediate partition strips extending transversely at each side of said handle portion, side walls depending at the respective extending ends of said partition strips, and a bottom wall connected between the

bottom edges of said side walls, the improvement which comprises a strut member secured medially of said carrier between said bottom wall and handle portion for supporting said bottom wall from said handle portion when the latter is raised for carrying, said strut member being recessed between said bottom wall and handle portion to form strap portions aligned with said intermediate partition strips and being substantially the same width thereof, and said strap portions being transversely foldable for collapsing laterally beneath the intermediate partition strips at one side of said handle portion to allow depression of said handle portion from said raised carrying position.

3. In a paperboard carrier, the structure defined in claim 2 and further characterized in that said handle portion is formed by a pair of handle panels secured in face-to-face relation, said bottom wall is formed by a pair of half laps secured medially of said carrier, and said strut member is formed by an extension of one of said half laps and is secured at the extending edge thereof between the panels of said handle portion.

4. A blank for a paperboard carrier, said blank being cut and scored to define a pair of foldably joined handle panels, end and intermediate partition strips foldably extending from each of said handle panels at the edges opposite the foldable joined edges thereof, side walls foldably joined at the respective extending edges of each of said end and intermediate partition strips, bottom wall half laps foldably joined at the outer edges of each of said side walls, a securing flap foldably joined at the outer edge of one of said bottom wall half laps, and an extension foldably joined at the outer edge of the other of said bottom wall half laps and extending therefrom in excess of the extent of said side walls between the foldably joined edges thereof, whereby said extension is proportioned for securing between said handle panels for supporting said bottom wall half laps therefrom, said extension being notched intermediately of its extent and thereby formed with strap portions aligned with said intermediate partition strips and being substantially the same width thereof, and said strap portions being transversely foldable for collapsing.
